UNITED STATES PATENT OFFICE.

ERWIN KLEIN, OF VOSLAU, NEAR VIENNA, AUSTRIA, ASSIGNOR TO THE FLEISCHMANN COMPANY, A CORPORATION OF OHIO.

APPARATUS FOR COMMUNUTING AND DRYING YEAST.

Original application filed March 24, 1922, Serial No. 546,502. Divided and this application filed June 17, 1922. Serial No. 569,112.

To all whom it may concern:

Be it known that I, ERWIN KLEIN, a subject of the Kingdom of Roumania, residing at Voslau, near Vienna, in the Republic of Austria, have invented new and useful Improvements in Apparatus for Communing and Drying Yeast, of which the following is a specification.

My invention relates to improvements in the manufacture of pressed yeast, especially to improvements in drying such yeast, and consists of an improved apparatus for drying pressed yeast in order to insure a more uniformly dried final product which will be in a condition better adapted to be influenced and improved by added substances suitable to enhance the effect of such yeast, than the yeast obtained by the hitherto known drying processes.

20 The commonly known processes and methods for drying pressed yeast consist in drying yeast by means of air passed through the particles of yeast which are obtained by dividing the yeast by means of oscillating 25 sieves, turning devices of different kinds and other means so as to reduce the yeast into a crumby or granulated mass. A still finer subdivision of the particles into a pulverized state has not been carried out in order to 30 avoid losses incurred by the flying away of the yeast in the form of dust together with the current of air.

For conserving the energy of the yeast during the drying process, the temperature 35 of the current of air employed for this purpose is not allowed to surpass a certain limit. Generally, this temperature of the current of air used in connection with a crumby or granulated mass of yeast is not 40 allowed to be higher than 10 to 15 degrees C. in the beginning of the drying process and may be raised to about 30 to 40 degrees C. in the final period thereof. The pressure of such air is about 3 atmospheres.

45 According to the present invention the process for drying pressed yeast is carried out by means of a current of air of higher temperature and of lower pressure than hitherto employed on account of the yeast 50 being brought into a most finely divided

state, preferably in a pulverized or dust-like state.

The fact that the yeast is brought into a most finely divided state allows of the use of air of low pressure, because a low pressure 55 is sufficient to bring the air into intimate contact with all fine particles of the yeast, whereas with only coarsely divided yeast, the pressure of the current of air must be materially above that of the atmosphere to 60 penetrate into the interior of the relatively large particles of yeast and to dry them.

Furthermore large quantities of air of more elevated temperature may be passed through the yeast owing to its finely divided 65 state on account of the dehydration of the yeast taking place so quickly that the particles of the yeast are not heated to the temperature of the current of air because they are cooled by the losses of heat created by 70 the evaporation of the content of water of the yeast particles.

The use of an elevated temperature of the current of air accelerates the drying process and renders it more economical. Contrary 75 to the known processes in which the subdivision is only carried out to such degree that the yeast particles cannot fly away in the form of dust, the process according to my present invention is executed in such a manner that the most feasible quantities of yeast are carried along with the current of air and brought thereby to a collector in which finishing of the drying to the desired content of humidity may be effected (if necessary or 80 desired) by means of a still more highly heated current of air.

The process is preferably carried out in the following manner. After a preliminary coarse subdivision of the yeast it is brought 90 into a closed container having a stirring or cutting device acting to bring the yeast gradually into a most finely divided state. The container is provided with air inlet and outlet ports and is supplied with a current 95 of air of a temperature of about 20 to 30 degrees and having a somewhat elevated pressure. This current of air, which may be dried previously, is passed into the container and through the yeast contained therein 100

until the degree of humidity of the yeast is lowered to about 30%. The current of air is then heated to about 50 degrees C. and regulated in such a manner that the particles 5 of yeast brought to the desired degree of humidity are carried along and supplied to a special container serving to collect the dust-like particles of yeast. This collector 10 may be provided with heating means thereby rendering possible, if desired, a final or additional drying of the yeast in the collector.

An apparatus constituting a preferred embodiment of my present invention suitable 15 to carry out the process above described essentially consists of a container provided with conduits serving for the inlet and outlet of a current of air and with an intermediate partition-bottom having apertures; the 20 yeast is deposited on this partition-bottom above which a device for pulverizing the yeast is arranged. In order that the current of air may come from all sides into the most efficient contact with the particles of yeast, 25 the apertures in the intermediate partition-bottom are formed in a special manner, and furthermore provisions are made that the finely divided particles of yeast are carried along with the current of air, leaving the 30 container and being conducted to a collector having compartments into which the particles of yeast of different size are deposited so that a sorting of the yeast is thereby obtained. The compartments of the collector 35 are each provided with heating means, which may be independently regulated in order to finally or additionally dry the yeast deposited therein to a greater degree if desired and to obviate condensing of humidity.

40 In order that my invention may be properly understood, I annex two sheets of drawings in which the preferred embodiment of my apparatus is illustrated.

Fig. 1 is a vertical view, partially in section, through my improved drying device together with the collector. Fig. 2 is a plan of the intermediate partition bottom consisting in essence of two superposed plates containing between themselves apertures for 45 the passage of air. In sector I of this figure the lower plate is illustrated, the upper plate being removed. Sector II shows the upper plate alone and in sector III the plates in super-position are illustrated. Figs. 3, 4 and 50 5 are vertical sections on the lines *a—a* and *b—b* and *c—c*, respectively of the sectors I, II and III. Fig. 6 is a vertical section on the broken line *d—d* of Fig. 2.

The container for the reception of the 60 yeast to be dried consists of a receptacle or basin 2 rotatable on its middle axis and having ball-bearings 1; above this receptacle there is arranged a fixed cover 3 hermetically sealing the receptacle by means of a liquid

seal of known kind. Axially of the receptacle a tube 5 extends downwards into which discharges the conduit 6 for the air, which has a concentric groove 7 filled with a liquid in which the tube 5 is immersed in order to secure an air-tight seal. The fixed cover is 65 provided with an outlet tube 8 passing to the collector 9. A pulverizing device is rotatably mounted in the depending portion of the fixed cover, and consists, in the illustrated example, of a plurality of cutter-blades 10 70 fixed to annular supports 11, 11 on the shaft 12. The working edges of these cutter-blades are arranged in a cylindrical surface and are formed in a screw-like manner. The cover is further provided with scrapers or 75 turners 13 extending from the lower side of the cover downwards to an intermediate partition bottom 15 mounted in the receptacle 2 and having vertical apertures 14. These scrapers plough and turn the yeast deposited 80 on this bottom 15 when the receptacle is rotated.

The collector 9 consists of a plurality of concentric shafts 16, 17, 18 enlarging conically on one end and discharging on the 85 opposite ends into a series of compartments 19, 20, 21, respectively, each of which is provided with heating means, for example with steam-serpentine 19^a, 20^a and 21^a, respectively. The shafts together with the 90 compartments are included within a common casing 22. This casing which is provided with doors (not shown) for the removal of the collected and dried yeast from the compartments 19, 20, 21 which are also 95 provided with suitable doors (not shown), encloses also the upper conical ends of the shafts and is provided at such upper portion with a heating device as indicated at 23 for preventing condensation. Baffle-plates 24, 100 105 are fixed on the upper wall of the exterior shaft and extend into the conical discharge ends of the other shafts. Air outlet ports 26 are arranged in the top plate of the casing, surmounted by a roof-like 110 cover 27.

The operation of the apparatus is as follows: The yeast to be dried is deposited through an opening (not shown) in the cover 3 on the intermediate partition bottom 15 of the receptacle 2 which is then rotated by means of a shaft 28 and of a toothed wheel 29 mounted on this shaft and of a toothed-wheel 30 provided at the outer circumference of the receptacle. The shaft 115 28 may be driven from any source of power. The shaft 28 simultaneously actuates, for example by means of the worm-gear within the casing 31, the shaft 12, rotatably mounted in the cover so that the cutter-blades 10 120 125 fixed thereto are brought into rotation.

By means of the conduit 6 suitably pre-heated air is supplied and is passed through

the apertures 14 and through openings existing between the superposed plates and comes then into contact with the yeast, thereby drying the same.

5 By the rotation of the receptacle 2 and of the intermediate partition bottom 15 the yeast deposited thereon is partly lifted and turned by the fixed scraper 13, the ends of which may have the form of rakes; simultaneously the yeast is gradually cut into smaller and smaller particles. The cutters also act as turning and distributing devices by partly turning, lifting and distributing the yeast.

10 The air flows out through the conduit 8 to the collector 9 and carries with it such small particles of yeast, the drying and pulverizing of which has taken place to such an extent as to allow their being swept 20 away by the current of air.

15 The particles of yeast carried away by the current of air are deposited for the most part in the compartment 19, part of the yeast, namely the lighter particles, is lifted by 25 the current between the walls of the shafts 16 and 17 (as indicated in Fig. 1 by arrows), is brought after passing the baffle-plates 24 into the space between shafts 17 and 18 and falls down into the compartment 30 20; the still lighter particles are again lifted by the current and are finally deposited, after passing the baffle-plate 25, in the compartment 21.

35 On account of the repeated change of the direction of the outflowing air caused by the baffle-plates, the particles of yeast carried along with the air are separated in their totality from the air so that practically air without any yeast particles leaves 40 the casing 22 through the opening 26.

The collector therefore acts as a device for separating the smallest dust-like particles of yeast from the current of air, so that losses are obviated. In order to free 45 the walls of the shafts from any particles of yeast adhering thereto and to collect them in the respective compartment, a vibrator is provided consisting of a stem 32 actuated by a cam 33 on the shaft 28 so as 50 to be pushed against the wall of the outer shaft 16. A tension spring brings the stem back to its original position. By the slight tapping of this stem upon the wall any particles of yeast adhering to the walls of the 55 shafts and to the baffle-plates are caused to fall down. Each compartment 19, 20, 21 is independently heatable, as already stated, for example by means of steam-pipes or the like for a further drying treatment of 60 the yeast. In order to obtain a good uniform drying of the yeast it is necessary that the air come into an intimate contact with all sides of the yeast particles. On account of the humidity the yeast tends to

form lumps and to choke the openings for 65 the passage of air thereby preventing a uniform contact of the air with and an efficient drying of the yeast. According to the invention the uniform contact of air under a low pressure with the yeast is obtained by a special shape of the intermediate partition bottom on which the yeast 70 to be dried is deposited.

This bottom essentially consists of two superposed plates 35, 37 which have there- 75 between a series of channels 39 in the shape of dies, each series of channels being provided in a sector of the plane, the lower and upper plate being divided into a series of sectors. The surface of the lower plate 80 consists in each sector of a series of bevelled or tapered planes 36, which are oblique and of which every two adjacent planes form together roof-like surfaces. In each sector part of the upper plate 37 is removed so 85 that an opening 40 is created. One edge of the remaining part of the upper plate is zigzag-lined and preferably provided with teeth 38, whereas the other radial edge is unbroken.

90 The form of the inclined or bevelled planes 36 of the lower plate 35 is diagrammatically shown in sector I of Fig. 2, in which the section-lines of horizontal planes with the bevelled planes 36 of the lower 95 plate are indicated by the zigzag lines $f-f$, $g-g$, $h-h$.

95 The lower sides of the points of the teeth 38 rest on the lower plate 35 along lines of the same level, i. e. along zigzag lines. On 100 account of the bevel of the planes of the lower plate the interstices 39 (Fig. 5) between these two plates, (the lower 35 and the upper plate 37), have the shape of a die lying in the direction of concentric cycles. 105 The discharge ends of these die-like channels 39 are divided by the teeth 38 of the upper plate 37 into a plurality of separate discharge openings. The current of air supplied by the conduit 6 passes through the 110 vertical ports 13 of the lower plate and enters the channels 39 between the lower and upper plate, discharging in the yeast deposited on the upper-plate. On account of the zigzag-form of the discharge end of the 115 channels 39 a relatively large cross-section of discharge is secured and the current is subdivided by the teeth 38 into single streams blowing in different directions. For further subdividing and distributing 120 the current of air the upper-plate 37 may be provided on its lower side with ribs resting on the upper surface of the lower plate so that a series of channels or compartments of different directions are formed through 125 which the air passes.

In order to prevent choking of the air inlets the die-like channels are situated in the

direction of concentric cycles and pass obliquely from below to above, thereby enabling removal of the yeast from the discharge openings when the yeast is ploughed by the scrapers on rotating the receptacle 2.

To prevent escape of air between the edges of the rotating receptacle and the fixed cover the latter is provided with an annular plate 42 the lower edge of which extends into a groove 4 of the receptacle 2, which groove is filled with liquid. By these means any loss of yeast is obviated.

A branch 43 of the air conduit 6 supplies air in the annular space between the plate 42 and the sides of the receptacle and of the cover so that the same air pressure is created therein, thereby assisting the seal formed by the liquid.

This application is divided from my application for United States Patent Serial No. 546,502, filed March 24, 1922.

What I claim as my invention and desire to secure by Letters Patent is:

1. In an apparatus adapted for drying compressed yeast, the combination of a receptacle having a flat bottom capable of supporting compressed yeast during the drying operation, means for passing a current of an aeroform drying fluid through the receptacle in contact with the yeast, and means for mechanically subdividing the yeast upon the bottom of the receptacle, said subdividing means and the bottom of the receptacle being movable with respect to each other about a vertical axis and said subdividing means including a comminuting member closely spaced from the bottom of the receptacle and extending across substantially its entire width.

2. Apparatus for drying pressed yeast comprising a container consisting of a rotatable receptacle and a superposed fixed cover, an air-tight seal between this receptacle and the cover, the rotatable receptacle having an intermediate partition bottom provided with ports, means for mechanically dividing the yeast fed to the said bottom, means for the supply of a current of air below this bottom and means for the outflow of air from above said bottom.

3. Apparatus for drying pressed yeast comprising a container consisting of a rotatable receptacle, and a superposed fixed cover, the rotatable receptacle having an intermediate partition bottom provided with ports and the fixed cover carrying means for mechanically subdividing the yeast fed to the bottom, means for the supply of a current of air below this bottom and means for the outflow of the air.

4. In an apparatus adapted for drying compressed yeast, the combination of a yeast-container provided with a flat perforated false bottom and means for passing a current of air therethrough in an upward direc-

tion, with means for mechanically subdividing the yeast upon said bottom, said subdividing means comprising cutter blades mounted on a rotating shaft with their cutting edges arranged spirally in a cylindrical surface in uniform close proximity to said bottom.

5. Apparatus for drying pressed yeast comprising a container consisting of a rotatable receptacle and a superposed fixed cover, an air-tight seal between this receptacle and the cover, the rotatable receptacle having an intermediate partition bottom provided with ports, means for mechanically dividing the yeast fed to the said bottom, means for the supply of a current of air through said bottom and also through a separate air inlet port positioned above said bottom and means for the outflow of air from above said bottom.

6. In an apparatus for drying pressed yeast, a container for the yeast, means for the inlet and outlet of a current of air into and out of the container, an intermediate partition bottom in the container upon which the yeast to be dried is deposited, this bottom consisting of two superposed plates leaving between themselves oblique channels, formed by bevelled and roof-like planes on the upper surface by the lower plate and of the even underside of the upper plate.

7. In an apparatus for drying pressed yeast, a container for the yeast, means for the inlet and outlet of a current of air into and out of the container, an intermediate partition bottom in the container upon which the yeast to be dried is deposited, this bottom consisting of two superposed plates leaving between themselves oblique channels, formed by bevelled and roof-like planes on the upper surface by the lower plate and of the even underside of the upper plate.

8. In an apparatus for drying pressed yeast, a container for the yeast, means for the inlet and outlet of a current of air in and out of the container, an intermediate bottom in the container upon which the yeast to be dried is deposited, this bottom consisting of two superposed plates, the lower plate having a series of bevelled and roof-like planes on its upper surface uniformly distributed over sections of the plate, the upper plate having an even underside and being partly interrupted in conformity with the sections of the lower plate, the underside of the upper plate confining channels with the bevelled and roof-like planes of the lower plate, leaving interstices between such surfaces, discharging through the interruption to the upper side of the upper plate.

9. In an apparatus for drying pressed yeast, a container for the yeast, means for the inlet and outlet of a current of air into

- and out of the container, an intermediate partition bottom in the container upon which the yeast to be dried is deposited, this bottom consisting of two superposed plates, 5 the lower plate having a series of bevelled and roof-like planes on its upper surface uniformly distributed over sections of the plate, the upper plate having an even underside and being partly interrupted in conformity with the sections of the lower plate, the underside of the upper plate confining channels with the bevelled and roof-like planes of the lower plate, leaving interstices between such surfaces, discharging through 10 the interruption to the upper side of the upper plate, the edge of the upper plate bordering the interruptions being saw-like toothed, the lower side of the points of the teeth resting on the lower plate, so as to 15 subdivide the current of air into separate streams.
10. In an apparatus for drying pressed yeast, a container having air inlet and outlet conduits, means for mechanically pulverizing the yeast to be dried, means for passing a current of air through the yeast and means for collecting the partly dried yeast carried away by the current of air, said means consisting of a series of container-shafts, arranged at a distance from the drying container and connected therewith, each container-shaft being provided with independent heating means and communicating with the other shafts so as to allow a sorting 25 and depositing of the particles of yeast carried along with the current of air.
11. In an apparatus for drying pressed yeast, a container having inlet and outlet openings, means for mechanically pulverizing the yeast to be dried, means for passing 30 a current of air through the yeast and means for collecting the partly dried yeast carried away by the current of air, said means consisting of a series of container-shafts, arranged at a distance from the drying container and connected therewith, these shafts being cylindrical and arranged concentrically and having conical enlargements on one end and discharging into closed compartments, each of which is independently heatable, and baffle-plates extending into and parallel to the conical enlargements of the shafts. 35
12. In an apparatus for drying pressed yeast, a container having air inlet and outlet ports, means for mechanically pulverizing the yeast to be dried, means for passing a current of air through the yeast and means for collecting the partly dried yeast carried away by the current of air, said means consisting of a series of container-shafts, arranged at a distance from the drying container and connected therewith, these shafts being cylindrical and arranged concentrically and having conical enlargements on one end and discharging into closed compartments, each of which is independently heatable, baffle-plates extending into and parallel to the conical enlargements of the shafts, and a vibrator acting on the shafts. 40
13. Apparatus for drying pressed yeast, consisting of a rotatable receptacle and of a fixed cover, an annular plate fixed to and surrounding the border of the cover and immersing into a liquid, contained in a groove of the dish, means for admitting air under pressure into the annular chamber between the plate and the cover border. 45

Dr. ERWIN KLEIN.
